UNITED STATES PATENT OFFICE.

BURTON O. WOOSTER, OF SAN JOSE, CALIFORNIA.

NAIL-STRIPPING DEVICE.

Application filed January 12, 1927. Serial No. 160,710.

My invention is an improvement in nail stripping devices, and it consists in the combinations, constructions and arrangements herein described and claimed.

5 An object of the invention is the provision of a nail stripping device which affords facilities for holding a mass of nails from which nails may be fed to position for convenient removal one or more successively at a time 10 for use as desired.

A further object of the invention is the provision of a nail stripping device of the character described which is adapted to be worn by a workman in position for use without interference with the movements of the 15 workman.

A still further object of the invention is the provision of a nail stripping device of the character described which is simple in 20 construction, economical to manufacture, reliable in use, and thoroughly practical commercially.

Other objects and advantages of the invention will be apparent from the following 25 description, considered in conjunction with the accompanying drawings, in which

Figure 1 is a perspective view of a nail stripping device embodying the invention as worn by a workman,

30 Figure 2 is a vertical section through the nail stripping device substantially along the line 2—2 of Figure 1, and

Figure 3 is a section through the nail stripping device substantially along the line 3—3 35 of Figure 1.

The improved device is particularly well adapted for use by lathers, shinglers and other workmen who have occasion to drive nails in rapid succession. Such workmen 40 ordinarily place quantities of nails in their mouths and remove such nails one at a time for use as required. This practice is likely to cause injury to the mouth or teeth of a workman and to detrimentally affect and thus 45 impair his general health.

The present invention aims to provide a device from which nails can be taken by a workman and placed in position for driving more conveniently and quickly than he could transfer nails from his mouth to position for driving and of course without the aforesaid possible injury to his general health, mouth or teeth.

The improved device comprises a receptacle 50 having a body 1 made of flexible material

such as a heavy grade of duck or other suitable fabric or material. The body 1 is open at its upper end and is closed at its lower end by a forwardly and upwardly inclined bottom plate 2 which may be made of a light 60 gauge metal or other suitable relatively rigid material. The bottom plate 2 may be secured to the body 1 in any suitable manner, as by being secured at intervals along its marginal edge by bolts and nuts 3 or like fastening devices to an overlapping lower edge portion 4 of the body. This plate 2 projects far enough outside of the duck to prevent the duck pouch from wearing out along the sharp edges of the metal plate. 65

The bottom plate 2 serves as a nail feeding plate and is formed with a plurality of spaced depressed portions 5, thus producing channels 6 in the inner face of the bottom plate. The depressed portions are provided with 70 longitudinal slots 7 through which the shanks of nails 8 may extend. These slots are located along the longitudinal median lines of the depressed portions 5 and are of less width than the diameter of the heads of the nails 75 so that the heads of the nails may slide along the channels 6 as the shanks of the nails are slid along the slots 7.

The forward and higher ends of the slots 7 are enlarged laterally at 9 to produce outlet 80 openings through which the heads of the nails may be moved one at a time from the channels 6.

The body 1 preferably enlarges in cross 85 sectional area from its upper end to its lower end and has its upper edge located in a plane which will be inclined downwardly and rearwardly when the receptacle is supported at the front of the body of a workman 10 by the neck strap 11 and is secured to the body of the workman by the 90 waist engaging straps 13 and 14 as shown in Fig. 1. The straps 13 and 14 may have their forward ends attached to opposite sides of the lower part of the receptacle body and 95 may be tied or otherwise secured together at the back of the wearer of the device and the neck strap may be a strap attached at its ends to the top of the body of the receptacle at opposite sides of the front of the latter so as to produce a loop that can be slipped 100 over the head of the wearer of the device.

From the foregoing description of the various parts of the device, the operation thereof may be readily understood. The work- 110

man places nails in the receptacle and the shanks of the nails drop downward through the slots 7. The shank of the foremost nail in each slot thus can be conveniently grasped 5 between the forefinger and thumb of a hand of the workman and the nail quickly and easily moved forwardly and upwardly as required to cause the head of the nail to move through the outlet opening 9. The nail can be placed 10 in position for driving by a continuation of the movement of the hand whereby the nail was removed from the device.

Obviously the invention is susceptible of embodiment in forms other than that which 15 is illustrated in the accompanying drawings and I therefore consider as my own all such modifications and adaptations thereof as fairly fall within the scope of the appended claims.

20 I claim:—

1. A nail stripping device comprising a receptacle having a downwardly enlarging flexible body and an upwardly and forwardly inclined plate-like bottom, said bottom hav-

ing a plurality of side to side narrow depressed portions, each producing a channel in the upper face of the bottom and each having a longitudinal slot formed therein, said slot being enlarged laterally at its forward end substantially to the full width of 30 the channel, as and for the purposes set forth.

2. A nail stripping device comprising a receptacle having a downwardly enlarging flexible body and an upwardly and forwardly inclined plate-like bottom, said bottom 35 having a plurality of narrow depressed portions, each producing a channel in the upper face of the bottom and each having a longitudinal slot formed therein, said slot being enlarged laterally at its forward or front end 40 substantially to the full width of the channel, said receptacle body being open at its upper end and having its upper edge lying in a plane that is inclined downwardly and rearwardly from the front portion of the receptacle 45 body.
